CLAIM

The ornamental design for an absorbent article top sheet with a pattern, as shown and described.

DESCRIPTION

FIG. 1 illustrates a front view of an absorbent article top sheet with a pattern;

FIG. 2 illustrates a perspective view of the absorbent article top sheet with a pattern;

FIG. 3 illustrates a left side view of the absorbent article top sheet with a pattern, with the right side view being identical; FIG. 4 illustrates a top end view of the absorbent article top sheet with a pattern, with the bottom end view being identical; and,

FIG. 5 illustrates a rear view of the absorbent article top sheet with a pattern.

The broken lines and the areas adjacent the solid lines of the claim depict environmental subject matter that forms no part of the claimed design.
